UNITED STATES PATENT OFFICE.

DAVID PEREZ AND HENRIETTA E. PEREZ, OF BUFFALO, NEW YORK.

DESIGN FOR A FLAG.

Application filed January 29, 1925. Serial No. 12,192. Term of patent 3½ years.

To all whom it may concern:

Be it known that we, DAVID PEREZ and HENRIETTA E. PEREZ, citizens of the United States, residing at Buffalo, in the county of Erie and State of New York, have invented a new, original, and ornamental Design for Flag, of which the following is a specification, reference being had to the accompanying drawing, forming part thereof.

The figure is a plan view of a flag, showing our new design.

We claim:

The ornamental design for a flag, as shown.

DAVID PEREZ.
HENRIETTA E. PEREZ.
